COLLAPSIBLE BOOK RACK

Anthony R. Perini, 6 Wall St., New Bedford, Mass.
Filed Oct. 27, 1961, Ser. No. 159,473
4 Claims. (Cl. 211—42)

The present invention relates to a simple, practical and economical openwork rack which is expressly constructed and designed to serve as a rack for books, magazines, newspapers and the like, and has reference to a construction which may rest upon the floor or, alternatively, other support or may be elevated and hung from a wall or an equivalent vertical support surface.

More specifically the invention in a preferred embodiment thereof is characterized, generally speaking, by a horizontally elongated crib-like rack embodying a pair of X-shaped leg-frames, a plurality of spaced parallel horizontally disposed rods having their ends connected to the leg-frames. With the leg-frames vertical and the rods horizontal and therefore at right angles to the leg frames, a V-shaped crib-like rack is provided.

A rack having these general characteristics but used as an album holder is disclosed in a patent identified as U.S. Patent 2,331,239 granted to L. L. Schock et al., October 5, 1943.

The invention also has to do with the construction stated and wherein a pair of top rods or rod members serve not only in connecting the leg frames together but also function to accommodate a pair of slides. These slides are alike in construction and are adjustable along said rod toward and from each other and function in selectively usable positions to assist one in bunching or stacking the books and then clamping the same in systematic but readily accessible positions. In this respect the slides function in a manner similar to book ends as disclosed in the generally similar construction identified as the Hackworth et al. book rack in U.S. Patent 2,134,606 of October 25, 1938.

An obvious objective in the instant matter is to structurally, functionally and otherwise improve upon the above identified patents and any similarly constructed and performing prior art racks. To this end, simple and practical bar or strip members are apertured and slidably mounted and function as the aforementioned book grouping and clamping slides.

Novelty is also predicated on having the uppermost rod members mounted so that the end portions project outwardly beyond their respectively adjacent leg frames, whereby to provide a practical construction capable of being hung and suspended from hooks or the like.

Then, too, these elongated horizontal rod members have their respective outer ends permanently connected with the cooperating intended upper ends of the legs of the respective leg frames and it is on these rod members that the two slides are slidably mounted. Conversely, the stated upper rod members are hingedly connected with the respective outer ends of the slides with the result that the slides have the additional function of linking the left and right sections of the rack together in such a way that these sections are capable of being disconnected from each other and spread flatwise in a plane coplanar with each other and with said slide for ready handling and transportation.

Other objects, features and advantages will become more readily apparent from the following description and the accompanying sheet of illustrative, but not restrictive, drawings.

In the accompanying drawing wherein like numerals are employed to designate like parts throughout the views.

FIGURE 1 is an elevational view of a book rack constructed in accordance with the principles of the inven-

2

tion and showing, in phantom lines, the manner in which books are grouped and racked systematically therein.

FIGURE 2 is a foreshortened top plan view of the same.

5 FIGURE 3 is a section on the vertical line 3—3 of FIGURE 1 looking in the direction of the arrows.

FIGURE 4 is an enlarged detail section and elevation on the line 4—4 of FIGURE 3.

10 FIGURE 5 is an enlarged fragmentary view in section and elevation on the line 5—5 of FIGURE 2.

FIGURE 6 is a fragmentary perspective view showing how a projecting end portion of one of the rods serves as a suspension member.

15 Referring now to the drawings it will be seen that there are two vertical spaced parallel end members which are here referred to as leg frames 8 and 10, respectively. Each frame is generally X-shaped in end elevation and made up of a pair of complementary legs 12, the central portions of which are notched and fitted together as 20 at 14 in FIGURE 6. Also and as perhaps best shown in FIGURE 4 these notched cross portions are separably joined by a bolt 16 held in place by an accessible wing nut 18. Disposed horizontally and at right angles to the leg frames 8 and 10 are rack forming rods which are 25 ordinarily in the form of elongated wooden rounds for dowels. The spaced parallel coplanar lower pair of rods 20 are shown in section FIGURE 3. The ends thereof are fitted into suitable holes provided therefor in the respective legs of crossed portions of the legs. The intermediate rods 22 (both at the left and right in FIGURE 3) have their ends likewise fitted into holes provided therefor in the legs and are glued or otherwise held in place. The uppermost rods 24 are circular in cross-section and serve 30 primarily as mounts for the pair of spaced parallel strip or bar members which are here referred to as slides 26. The end portions (FIGURE 5) of the slides have circular holes therein as at 28 and the holes are slightly larger than the cross section of the cooperating rods 24. Metal clips 30 are positioned in intended half-portions of the holes 40 28 and suitably embedded in the slides 26 and have arcuately bent portions 32 which are springy and slightly under tension and serve as friction shoes. These friction shoes serve to engage the rods 24 and consequently it is possible for one to shift or move the slides closer together or farther apart from the outward full line positions as shown in FIGURES 1 to 3. In other words, one may adjust the slides to the dotted line positions shown in FIGURES 1 and 2 where they serve to bunch a group of books and in fact may be pressed sufficiently tight 45 against the books to clamp the books against falling or displacement.

50 The respective outer end portions of the rods 24 are extended beyond the holes 34 provided in the legs, as seen in FIGURE 6. These extending end portions 36 project sufficiently far that they serve as convenient suspension terminals and hence may be supported by way of hanger hooks 38 mounted in the wall or other vertical surface 40. This makes it possible to conveniently suspend the rack on the wall. For the most part the rack will rest on the floor or other horizontal support surface as shown in FIG. 1.

55 It will be obvious that by unfastening the crossed notched portions of the overlapping legs of the respective leg frames 8 and 10, the over-all rack may be collapsed. This procedure simply requires removing the bolts 16 by first detaching the thumb nuts 18. Then, the notched portions of the legs can be separated and the leg frames can be swung out in a plane common with the slides 26 or, the parts may be folded or collapsed in any 60 handy or convenient manner (not shown) for shipping and storing. Accordingly, it will be evident that the structure, construed as a ready-to-use unit, resembles an open-

work crib-like rack and that the rods 29 are close together and provide a sturdy bottom as is evident from FIG. 3. Also, the shiftable strip members 26 serve not only as slides for variable book assembling and clamping needs, they also function as the means which links the two frames or sections (one inclined right to left and the other inclined left to right in FIG. 3) to each other. Stated otherwise, these frames are hinged on and linked together by the slides 26.

The foregoing is considered as illustrative only of the principles of the invention. Further, since numerous modifications and changes will readily occur to those skilled in the art, it is not desired to limit the invention to exact construction and operation shown and described, and accordingly all suitable modifications and equivalents may be resorted to, falling within the scope of the invention as claimed.

What is claimed as new is as follows:

1. A portable book rack comprising a pair of vertical spaced parallel X-shaped leg frames, each leg frame comprising a pair of crossed interlocked separably fastened legs, a first pair of relatively low horizontal parallel contiguous rod members having their respective outer ends connected to the respective legs of the crossed portions of the respective leg frames, a second pair of upper horizontal rod members having their end portions connected to the upper ends of their respective legs of the respective leg frames and projecting outwardly beyond said legs, a plurality of intermediate rod members arranged in planes between the upper rod members and lower rod members and connected at their ends to their respective legs of the respective leg frames and providing a crib-like book rack, and a pair of bar members disposed at right angles to and having apertured end portions frictionally slidable along said upper rod members.

2. A book rack comprising an openwork crib normally open at its top and a pair of vertical spaced parallel X-shaped leg frames each the same in construction and embodying a pair of companion legs having their respective median portions crossing each other and separably fastened together in a manner defining said X-shaped leg frames, a first pair of relatively low elongated rod members disposed in close-spaced parallelism, lo-

cated adjacent to and just above the plane of the crossing portions of the legs of the respective pairs and having outer ends permanently connected to their respective legs at the ends of said crib, a second pair of similar horizontal elongated rod members disposed in a plane above the plane of the first-named rod members and having outer end portions thereof permanently connected with their respective upper end portions of the legs of the aforementioned pairs of legs, and a pair of bar members disposed at right angles to and having apertured end portions manually slidable and shiftable along said upper rod members, said bar members providing book assembling and clamping slides, and also serving to hingedly link and connect said rod members to each other in spaced apart parallel relationship.

3. The structure according to claim 2 and wherein peripheral portions of the apertures provided in said bar members are partially lined with resilient friction springs, said springs having friction contact with cooperating surfaces of said second-named rod members whereby to permit the bar members to be individually or conjointly adjusted toward and from each other or toward and from the respective vertical leg frames and frictionally held in adjusted position.

4. The structure according to claim 2 and wherein the respective outer end portions of said second-named rod members project outwardly and beyond the adjacent outer surfaces of the respective cooperating legs, said projecting end portions being adapted to accommodate and be engaged with suspension hooks or the like on a stationary vertical wall whereby said rack is thus suspended for use from said vertical wall.
